[57] CLAIM

The ornamental design for a controller for computer printing system, as shown and described.

DESCRIPTION

FIG. 1 is a front view of the controller for computer printing system;

FIG. 2 is a rear view thereof;

FIG. 3 is a top plan view thereof;

FIG. 4 is a bottom plan view thereof;

FIG. 5 is a side elevational view as seen from the left of FIG. 1;

FIG. 6 is a side elevational view as seen from the right of FIG. 1;

FIG. 7 is a cross-sectional view of the housing taken on line 7—7 of FIG. 1;

FIG. 8 is a cross-sectional view of the housing taken on line 8—8 of FIG. 1; and

FIG. 9 is a perspective view of the controller for computer printing system.
